UNITED STATES PATENT OFFICE.

PASCAL SYLVESTER, OF CHICAGO, ILLINOIS, ASSIGNOR TO PASCAL SYLVESTER, INC.,
A CORPORATION OF ILLINOIS.

GRILLE.

Application filed September 7, 1926. Serial No. 133,800.

My invention relates to improvements in grilles for terrazzo floor constructions and is particularly adapted for use in the making of that type of terrazzo flooring in which various designs are laid out with terrazzo of contrasting color or texture.

The principal object of the invention is to provide factory made units which may be delivered to the job in condition ready to be placed in the floor without the necessity of doing extensive manual work on the grille work preparatory to laying the terrazzo.

I am aware that heretofore ornamental terrazzo flooring has been laid by means of metallic strips laid edgewise in the terrazzo surface for marking the boundaries of the terrazzo area of contrasting colors. However, so far as I am advised, such grillage has heretofore been made up on the job itself from individual strips of metal bent to the shape of the design desired and positioned on the floor base individually.

The old method has been fairly successful in the case of very plain designs relatively free from curvilinear outlines, but has not been commercially successful for use with complicated or highly ornamental designs having curved boundaries. According to my invention the grillage desired for producing these more or less intricate or curvilinear designs is made up in advance as a factory proposition and all the work required of the men on the job is to take the completed grillage or grillage units and lay them in position on the floor. With my improved units it is not necessary to cut the strips or curve them or connect with other strips while the work is going on.

In the drawings accompanying this application and illustrating a selected embodiment of my invention:

Fig. 1 is a perspective view of one of my improved grillage units;

Fig. 2 is a plan view of a section terrazzo flooring showing the manner in which the grillage unit is utilized in making the floor, and

Fig. 3 is a section taken on the line 3—3 of Fig. 2.

Referring to the drawings, it will be seen that my grille unit is composed of strip metal, preferably brass, all of the strips being cut from a continuous strip of uniform and rectangular cross section. The strip is perforated at intervals as shown at 10. These apertures 10 are provided to enable the cement of the terrazzo filling to enter the apertures and thus form a bond preventing the subsequent displacement of the grille or parts thereof after the terrazzo has set.

It will be observed that the apertures 10 are relatively narrow with respect to their vertical dimensions while being elongated lengthwise of the strip. Thus each aperture may be made of considerable area, for the purpose of providing a proper bond, while at the same time, owing to the narrowness of the aperture the bending of the strip into a regular curvilinear form is not interfered with.

It will be observed by reference to the perspective view in Fig. 1 that the main elements of the structure comprise a pair of continuous curved sections 11 and 12 to which are connected pairs of shorter curved members 13, 14, 15, and 16. These six members constitute the outlines of the areas 17, 18, 19, and 20, see Fig. 2. The intermediate areas 21, 22, 23 and 24 of the design are produced by connecting pairs of shorter similarly curved strips 25, 26, 27, 28, 29, 30, 31, and 32.

It is desirable that the connecting or reinforcing means by which the various elements of the grillage are connected together should not appear at the surface of the terrazzo which should display only the edges of the boundary strips as shown in Fig. 2. For this reason the connecting means are located wholly below the top plane of the grillage. It is also desirable that the bottom plane of the grille should be flat so that when the grille is applied to the underlying concrete base, the top edge faces of the various strip portions of the grille will all be located in the top plane of the terrazzo face when the latter is finished. Therefore, the connecting means should also, if possible, preferably lie above the bottom plane of the grillage. Incidentally by locating the connecting elements or

means intermediate the top and bottom planes of the grille, such connecting elements furnish an additional bond for preventing displacement of the strips after the terrazzo floor 5 is finished.

In the embodiment shown, the strips are preferably united together by soldering at each point where the ends or other surfaces of the component parts abut or come together.

10 This is shown for example at points 33, 34, and 35 in Fig. 1.

In the case of a design composed largely of curved members as in the sample design herein illustrated, I prefer to employ a plurality 15 of additional reinforcing members. In the present instance, straight wires or rods do the work quite satisfactorily. With reference to Fig. 1, it will be seen that I employ four continuous rods 36, 37, 38 and 39. The rods 20 at their ends as at 39 are soldered to the inner faces of the outer strips and extend through notches or apertures in the intermediate strips as indicated at 40. Preferably the several rods of the reinforcing system are ar- 25 ranged to intersect as indicated at 41, the intersecting rods being relatively offset so as to pass each other.

Wherever the rods intersect each other as shown at 41 or pass through apertures in the 30 intermediate strips, they are united to each other or to the strips by means such as soldering.

By means of the construction shown, there may be produced as a factory proposition, 35 and at relatively small expense, complete grillage units all made up in advance and ready to be laid by the workmen on the job without the necessity of connecting the various parts together or doing any other me- 40 chanical work on the grillage itself. Such grillage is used in the following manner.

On the sub-base which may be tile or concrete, there is placed a layer of fine sand- 45 cement concrete 42 which is screeded off to a uniform horizontal surface 43 which furnishes the base for the terrazzo layer 44. After the base 42 is set sufficiently, the grille units are located thereon in proper relative 50 position to make the desired design and the areas enclosed thereby are filled with a terrazzo mix of the proper color. The re- 55 mainder of the flooring space around the units is then filled with terrazzo of a contrasting color, the subsequent steps of the process being the same as ordinarily practiced by those skilled in the art.

Under the old practice the laying out and the making of an ornamental terrazzo flooring of contrasting colors was a slow and tire- 60 some process frequently resulting in the tying up of an expensive building until the work was completed. Also, owing to the slowness and length of the time necessary to lay out the design and position the strips

after the supporting base was finished, care 65 had to be taken to insure a satisfactory bond between the terrazzo surface layer and the upper surface of the underneath base layer which, in many cases, had become quite dry owing to the length of time necessary to lay 70 out and make the design. In view of the rapidity with which the entire grille design may be laid with my improved units, the making of a satisfactory bond or weld be- 75 tween the base and the terrazzo is greatly 80 facilitated.

From a labor and cost saving standpoint 85 the advantages of my factory made units will be recognized by those having to do with building or construction work, as it is well 90 understood that the cost of making an article in the field is usually several times the cost of making up the article in advance in a factory.

The details of construction herein dis- 85 closed being illustrative of only a single application of my invention, it will be understood that the scope of same should be determined by reference to the appended 90 claims, said claims being construed as broad- 95 ly as possible consistent with the state of the art.

I claim as my invention:

1. A factory made element for making ornamental terrazzo flooring comprising a 95 metal grille unit of uniform depth composed of strips of rectangular cross section having their opposite narrow edge faces located re- 100 spectively in the top and bottom planes of the unit, means for uniting together said strips located between the top and bottom planes of the grille, and reinforcing members located below the top plane of the grille con- 105 nnecting the strips of the grille and tying the said strips against lateral shifting movement between said planes.

2. A factory made element for making ornamental terrazzo flooring comprising a metal grille unit of uniform depth composed of strips of rectangular cross section having 110 their opposite narrow edge faces located re- spectively in the top and bottom planes of the unit, means for uniting together said strips located between the top and bottom plane of the grille, and wires located below 115 the top plane of the grille connecting the strips of the grille and tying the said strips against lateral shifting movement between said planes.

3. An element for making ornamental ter- 120 razzo flooring comprising a metal grille unit composed of a plurality of relatively wide but thin, metal strips arranged relative to each other so as to form the desired pattern, 125 said strips having their opposite narrow edge faces located respectively in the top and bottom planes of the unit, and means for tying said strips together so as to maintain the

same in said arrangement, said means comprising a plurality of wires extending between and anchored to some of said strips.

4. An element for making ornamental terrazzo flooring comprising a metal grille unit composed of a plurality of united relatively wide but thin metal strips arranged on edge and positioned to form the desired pattern,

said strips having their upper narrow edge faces located in a plane common to all, and constituting the top plane of the unit, and a plurality of reinforcing members disposed below said top plane, extending between and anchored to some of said strips for maintaining the strips in said arrangement.

PASCAL SYLVESTER.
